Specification for Design.

Patented Apr. 26, 1921.

Application filed April 13, 1920. Serial No. 373,559. Term of patent 14 years.

To all whom it may concern:

Be it known that I, MAURICE HIPPOLYTE LOUIS SIZAIRE, a citizen of the French Republic, residing at Park Royal, London, N. W. 10, England, in the county of London, have invented a new, original, and ornamental Design for an Automobile-Radiator, of which the following is a specification, reference being had to the accompanying drawing, forming part thereof.

Figure 1 is a front elevation,
Fig. 2 is a side elevation,
Fig. 3 is a plan of Fig. 2 and
Fig. 4 is a perspective view of an automobile radiator showing my new design.

I claim:—

The ornamental design for an automobile radiator as shown.

MAURICE HIPPOLYTE LOUIS SIZAIRE.
